DESCRIPTION

FIG. 1 is a perspective view of the arrow showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the FIGS. 1-7 illustrate portions of the arrow which form no part of the claimed design. Additionally, the dash-dot broken lines denote the boundary of the claim and form no part of the claimed design.
